UNITED STATES PATENT OFFICE

CHARLES M. TURSKY, OF PHILADELPHIA, PENNSYLVANIA

FLUID COMPRESSOR

Application filed May 19, 1931. Serial No. 538,473.

This invention relates to apparatus of the type forming the subject matter of Letters Patent of the United States granted to me and respectively Nos. 1,871,824 dated March 15, 1921; 1,478,929 dated December 25, 1923; and 1,533,958 dated April 14, 1925; wherein a pair of axially alined rigidly connected pistons are adapted to be reciprocated by a crank member carried between said pistons 10 and fitted to reciprocate transversely to the axis of said pistons and having at its outer end a ball fitted in a socket in a crank disk mounted to rotate on an axis at right angles to the axis of said pistons.

15 My present improvements relate particularly to the combination of such a piston with valve means for automatically controlling the intake and exhaust of fluid from cylinders in which said pistons are mounted to reciprocate; and to a gear driving device for rotating said crank disk, particularly adapted for driving the compressor by an electric motor rotating at a speed much higher than that of said crank disk.

20 My invention includes the various novel features of construction and arrangement hereinafter more definitely specified.

In said drawings; Fig. I is a right hand end elevation of a convenient embodiment of 30 my improved compressor in connection with an electric motor.

Fig. II is a partly sectional front elevation of the structure shown in Fig. I, section being taken on the vertical line II, II, in Fig. I.

35 Fig. III is a vertical sectional view of the compressor shown in Figs. I and II, taken on the line III, III, in Fig. II; the electric motor being indicated in right hand side elevation.

40 In said figures; the compressor casing comprises two separable sections, viz., the base section 1 having the pedestal flanges 2 with holes 3 for bolts 4 by which it may be rigidly connected with any suitable support; and 45 the other section 6 which is separable from the section 1 on the plane 7 but rigidly connected therewith by the four bolts 8 shown in Fig. II, so as to form a receptacle 9 for lubricating oil at the bottom of said casing.

50 Said casing section 1 supports the crank

shaft 10 which is journaled therein independently of said casing section 6. As shown in Fig. III, said shaft 10 is provided with two opposite thrust bearings comprising the respective series of rollers 11 and 12, which bear upon race rings 13 and 14 on said shaft which has the flange 16 as an abutment for the ring 13 and the collar 17 as an abutment for the ring 14; said collar being detachably connected with said shaft by any suitable means, conveniently the tapered pin 18. Said rollers 11 and 12 respectively bear upon the race rings 20 and 21 which are fitted in said casing section 1 and held in proper axially spaced relation by the spacing ring 22 between them. Said ring has the smooth drilled socket 23, shown in Fig. III, to receive the smooth cylindrical end 24 of the set screw 25 normally held by the set screw 26 in said casing section 1. In the position shown, said set screw 25 prevents axial and rotary movement of said spacing ring 22 and thus prevents longitudinal movement of said crank shaft 10. However, when said screw 25 is retracted to free its end 24 from the socket 23; said crank shaft 10 with its bearings aforesaid may be readily installed in or removed from said casing section 1.

Said casing section 6 has, in unitary relation therewith, axially alined cylinders 28 and 29, in spaced relation, upon respectively opposite sides of the axis of said shaft 10. The pair of pistons 31 and 32 are rigidly connected in spaced relation by the rod 33 which has the crank pin bearing 34 transverse to the common axis of said pistons. The crank pin 35 is mounted to reciprocate in said bearing 34 and has the ball end 36 fitted in the ball socket 37 in the disk 38 carried by said crank shaft 10 and conveniently formed in unitary relation therewith, as shown in Fig. III. The ball socket plate 40 is complementary to said socket 37 and is detachably secured to said disk 38, conveniently by three screws 41, in a circumferential series, one of which is shown in Fig. II and another in Fig. III.

The body of lubricating oil 44 which is held in said casing may be conveniently introduced through the openings 45 within the

cylindrical flange 46 at the top of said casing section 6, shown in Fig. III. Said inlet is, however, normally covered by the cap 47 held by the screw 48 engaging said section 6; 5 said cap being held in spaced relation with said flange 46 by a circular series, of, conveniently three, ribs 49 in the cap. During the operation of the compressor, said openings 45 serve as a "breather" inlet and outlet with respect to said casing section 6. Said casing section 1 has holes 51 and 52 extending through the pedestal flanges 2 at respectively opposite sides of said section 1 and conveniently drilled in axial alignment. 15 Said hole 51 is in communication with the oil sight gage indicated in Fig. I which includes the tubular metal fitting 54 containing the glass cylinder 55 secured therein by the knurled plug 56. Said fitting 54 has rigidly 20 connected therewith the gage plate 57 with the notch 58 therein indicating the desired minimum and maximum level of said body of oil 44. Said hole 52 serves as a drain outlet for dirty oil and is conveniently provided with the removable screw plug indicated at 60, as shown in Fig. II.

The oil feeding ring 61, shown in Fig. III, encircles said shaft 10, is free to turn thereon in eccentric relation therewith, and dips into the body of oil 44 in said receptacle 9. Said disk 38 has the oil receiving flange 62 and groove 63 in concentric relation with said shaft, and said ring 61 is held in cooperative relation therewith by said abutment flange 16 on said shaft; so that, as the shaft turns, oil is lifted by said ring and scraped off by said flange into said groove, with which said ball socket 37 communicates as indicated in Fig. III. Consequently, as the shaft 10 turns, oil is caused to flow from said groove 63 through said socket 37, to not only lubricate the latter but also flow into the oil passage 65 in said crank pin 35. Said passage 65 has lateral openings 66 through which oil 45 is not only supplied to the crank pin bearing 34 in the piston rod 33, but also into the oil passages 67 in said rod and thence through outlets 68 leading from said passages 67, respectively into said cylinders 28 and 29 to lubricate them, and the pistons 31 and 32 which respectively reciprocate therein.

Said crank shaft 10 may be thus rotated to oil all the parts connected therewith as above described, by any suitable means. For 55 instance, said shaft may be extended through the casing section 1 to the right in Fig. III and be connected with an electric motor or other operating means. However, I prefer to form upon the periphery of said disk 38 the circular series of gear teeth 70 which mesh with the teeth on the driving gear 71 which is carried by the driving shaft 72 in said casing members 1 and 6, parallel with said crank shaft 10, as shown in Fig. III. 60 Said shaft 72 is journaled in the opposite

thrust bearings comprising circular series of rollers 73 and 74 respectively mounted in the race rings 75 and 76 in said casing sections 1 and 6 and bearing upon the race rings 77 and 78 carried by said shaft 72; so that the endwise movement of said driving shaft is normally prevented. However, when said casing sections are separated by removal of the bolts 8, said shaft and its bearings may be readily removed therefrom.

As shown in Fig. III, said driving shaft 72 is provided with the crown clutch member 80 in rotary engagement with the similar clutch member 81 carried by the armature shaft 82 of the electric motor 83. I prefer to interpose between said clutch members 80 and 81 resilient elements 84 so as to permit slight relative movement thereof and thus facilitate the transmission of power from said motor to said compressor. Such an arrangement permits the operation of the compressor by a small high speed motor. However, the compressor may be otherwise operated as above indicated.

As shown in Fig. II, said cylinders 28 and 29 are provided with similar removable heads 85 and 86 which are detachably secured to said cylinders by respective circular series of four bolts 87 and 88. Said heads hold respective valve casings 90 in recesses 91 at the ends of the cylinders, in fluid tight relation and said casings have annular recesses 92 in which are fitted flexible annular valves 93 for controlling the fluid inlet ports 94 which lead to the outer atmosphere through the ports 95 in said casings; the latter ports being conveniently provided with elbow fittings 96 carrying silencers 97 which suppress the noise which would otherwise be made by the influx of air to said cylinders, as the pistons 31 and 32 are reciprocated, by the means above described. Each of said valves 93 conveniently consists of a plurality of thin sheet metal stampings. Although I have shown but two such stampings in Fig. II, I prefer to use more of thinner metal. For instance, spring tempered shim steel of, say, .002 of an inch thickness. The outer edges of said valve members 93 are held in substantially immovable relation with said cylinders but said valves are so flexible that they are adapted to bend into curved conical form like the discharge end of a trumpet when said pistons 31 and 32 are alternately retracted toward the axis of the crank shaft 10 to create a partial vacuum between the outer ends of the cylinders and said valves 93, to then and thus open said inlet ports 94 and permit the influx of air to the respective cylinders under atmospheric pressure through said silencers 97, etc. However, as said pistons 31 and 32 are thrust by the rotation of said crank shaft 10, each of said valves 93 is permitted to return, and in fact forced to return, to its normal plane form shown in Fig. II.

Each of said cylinders 28 and 29 is provided with a discharge port 99 in coaxial relation therewith, which is normally closed by a valve 100 under pressure of a spring 101, the stress of which determines the pressure at which the air or other fluid shall be discharged from the respective cylinders. Said valves 100 are conveniently formed of pressed sheet metal including a central disk having 10 three or more prongs 102 by which it is guided in its reciprocation in the valve chamber 103 in said casing 90. Said valve chambers 103 are respectively provided with outlet ports 104 through which the compressed fluid is discharged. As indicated in Fig. II, such outlet port from the cylinder 28 is provided with the elbow fitting 105 and the outlet port from the cylinder 29 is provided with a T-fitting 106. Said fittings are conveniently of the pinch type and connected by the manifold conduit 107 so that the fluid compressed in both of said cylinders 28 and 29 to the same pressure, is discharged through the common conduit 108 in which substantially 25 constant fluid pressure is maintained, by the alternate compressing operation of said pistons 31 and 32, as above described.

However, the fluid may be compressed to different pressures in the cylinders 28 and 29, 30 by the same means above described, if the fitting 105 which, as shown in Fig. II, is the discharge outlet of the cylinder 28 be connected to the inlet fitting 96 of the other cylinder 29, instead of to the discharge outlet fitting 35 106 of the cylinder 29; said fitting 106 being then capped or otherwise closed where it is shown connected with the conduit 107. The effect of the latter arrangement is that the fluid is initially compressed in the cylinder 28 40 to a pressure determined by the stress of the spring 101 local thereto and that fluid is further compressed, in the cylinder 29, to a higher pressure determined by the stress of the spring 101 local to the cylinder 29, and 45 the doubly compressed fluid discharged through said conduit 108.

I find it convenient to dissipate the heat liberated from the compressed air by means 50 of annular ribs 110 and 111 on the respective cylinders 28 and 29 and by radial ribs 112 on said heads 85 and 86.

The form of valves 93 and 100 above described may be advantageously employed in the compressor shown because they are operable with the minimum amount of clearance of the pistons 31 and 32 with respect to the outer end closures of the respective cylinders 28 and 29. However, I do not desire to limit 55 myself to the precise details of construction and arrangement herein set forth, as it is obvious that various modifications may be made therein without departing from the essential features of my invention, as defined 60 in the appended claims.

I claim:

1. In a fluid compressor, the combination with a substantially closed casing; of a crank shaft journaled in said casing; said casing being divided in two sections in a plane transverse to the axis of said shaft; one of said sections containing bearings for journaling said shaft independently of the other section; said other section of said casing having, in unitary relation therewith, axially aligned cylinders, in spaced relation, upon respectively opposite sides of the axis of said shaft; means detachably rigidly connecting said casing sections; said other casing section having an opening opposite to said crank shaft and provided with a removable door; a pair of pistons rigidly connected in spaced relation by a rod and mounted to reciprocate in the respective cylinders; a bearing in said rod transverse to the common axis of said pistons; a crank pin mounted to reciprocate in said bearing in the piston rod and having a ball end; said crank shaft having in eccentric relation therewith a ball socket fitted to said ball; said ball socket comprising a plate encircling said crank pin and having means detachably securing it to said crank, accessible for removal when said door is open; whereby, said casing is readily separable for access to the compressor elements within it.

2. In a fluid compressor, the combination with a casing, forming a receptacle for lubricating oil in the bottom thereof; of a crank shaft journaled in said casing, with its axis substantially horizontal; a disk on said shaft arranged to dip into said oil receptacle; an oil receiving flange on said disk, in concentric relation with said shaft; an oil feeding ring encircling said shaft, free to turn thereon in eccentric relation therewith, and dipping into said oil receptacle; means on said shaft for holding said oil ring in cooperative relation with said oil receiving flange; a ball socket in said disk, opening within the circumference of said oil flange; whereby oil is lifted into said socket by said ring during the rotation of said shaft, a piston rod mounted to reciprocate in said casing, transversely with respect to the axis of said shaft, and having a crank pin bearing extending transversely to its axis in a plane parallel with the axis of said shaft; a crank pin mounted to reciprocate in said bearing and having a ball end fitted in said socket; said crank pin having an oil passageway in communication with said socket and leading into said piston rod bearing; whereby rotation of said crank shaft causes oil to flow from said socket to lubricate said crank pin in its bearing.

3. In a fluid compressor, the combination with a casing, forming a receptacle for lubricating oil in the bottom thereof; of a crank shaft journaled in said casing, with its axis substantially horizontal; a disk on said shaft

- having gear teeth arranged to dip into said oil receptacle; a driving gear engaging said teeth; an oil receiving groove on said disk, in concentric relation with said shaft; an oil feeding ring encircling said shaft, free to turn thereon in eccentric relation therewith, and dipping into said oil receptacle; means on said shaft for holding said oil ring in cooperative relation with said oil receiving groove; a crank pin socket in said disk, opening into said groove, whereby oil is lifted into said socket by said ring during the rotation of said shaft; a piston rod mounted to reciprocate in said casing, transversely with respect to the axis of said shaft, and having a crank pin bearing extending transversely to its axis in a plane parallel with the axis of said shaft; a crank pin mounted to reciprocate in said bearing in the piston rod and having one end fitted in said socket; said crank pin having an oil passageway leading into said bearing; whereby rotation of said crank shaft lifts oil to said driving gear, socket, and said bearing.
4. A fluid compressor as in claim 2, wherein the piston rod has an oil passageway in communication with the oil passageway in said crank pin for discharging oil upon the surface traversed by the piston; whereby rotation of said crank shaft effects lubrication of both the crank and piston.
5. In a fluid compressor, the combination with a substantially closed casing, divided in two sections, in a plane transverse to its axis; of a driving shaft provided with opposite thrust bearings respectively mounted in said casing sections; and means detachably rigidly connecting said sections; whereby endwise movement of said driving shaft is normally prevented, but said shaft and bearings may be readily installed and removed when said casing sections are separated.
6. In a fluid compressor, the combination with a casing, divided in two sections, in a plane transverse to its axis; of a crank shaft journaled in said casing, in coaxial relation therewith; a gear carried by said crank shaft and carrying a crank pin eccentric to said axis; a driving shaft journaled in said casing, and extending exterior thereto, parallel with said crank shaft and eccentric thereto; a driving gear carried by said driving shaft in mesh with the gear on said crank shaft; means detachably rigidly connecting said sections; and a piston mounted to reciprocate in said casing with its axis transverse to the axis of said casing and operatively connected with said crank pin.
7. A fluid compressor as in claim 6, including two pistons having means rigidly connecting them in coaxial relation, spaced upon opposite sides of the axis of said crank shaft; a bearing for said crank pin, carried by said pistons, intermediate thereof; where-

by said pistons are simultaneously reciprocated by rotation of said driving shaft.

8. In a fluid compressor, the combination with a substantially closed casing, divided in two sections, in a plane transverse to its axis; of pedestal means on one of said sections for supporting said casing with its axis parallel with the supporting surface; a piston mounted to reciprocate in said casing; mechanism in said casing for reciprocating said piston; and means detachably rigidly connecting said sections; whereby said casing may be opened to afford access to the mechanism therein while the other casing section remains rigidly connected with its support.

In testimony whereof, I have hereunto signed my name at Conshohocken, Pennsylvania, this fifteenth day of May, 1931.

CHARLES M. TURSKY.
